No. 641,158.

W. L. SKELLEY.
COMBINATION STEP LADDER.
(No Model.)

Patented Jan. 9, 1900.

(Application filed Oct. 4, 1899.)

UNITED STATES PATENT OFFICE.

WALTER L. SKELLEY, OF CABOOL, MISSOURI, ASSIGNOR OF ONE-HALF TO
CARL E. GRANT, OF SAME PLACE.

COMBINATION STEP-LADDER.

SPECIFICATION forming part of Letters Patent No. 641,158, dated January 9, 1900.

Application filed October 4, 1899. Serial No. 732,487. (No model.)

To all whom it may concern:

Be it known that I, WALTER L. SKELLEY, of Cabool, in the county of Texas and State of Missouri, have invented a new and Improved 5 Combination Step-Ladder, of which the following is a full, clear, and exact description.

The object of my invention is to provide a combination long and a step ladder, the sides of which when used as a long or extended 10 ladder constitute each a truss and the hinges central struts for the same, rendering the extended ladder exceedingly staunch and permitting the ladder to be made very light.

Another object of the invention is to provide a means whereby the platform of a step-ladder and the parts connected therewith may be utilized to securely lock and brace the sections of the ladder when said sections are brought end to end to form a continuous or 20 long ladder.

A further object of the invention is to so construct the ladder that it may be quickly and conveniently converted from one form to the other, and whereby the ladder in both of 25 these forms will be not only light, but durable, thoroughly braced, and capable of ready manipulation.

The invention consists in the novel construction and combination of the several parts, 30 as will be hereinafter fully set forth, and pointed out in the claims.

Reference is to be had to the accompanying drawings, forming a part of this specification, in which similar characters of reference indicate corresponding parts in all the figures. 35

Figure 1 is a perspective view of the improved ladder utilized as a step-ladder. Fig. 2 is a longitudinal vertical section through the improved ladder when the members of the 40 ladder are brought together and secured to form an upright or long ladder, the view being drawn on a larger scale than the view shown in Fig. 1 and the section being taken practically on the line 2 2 of Fig. 3. Fig. 3 is an under side view of the central portion 45 of the extended or long ladder; and Fig. 4 is a longitudinal section through the platform of the ladder and the members to which the platform is attached, the members being folded together. 50

As usual in step-ladders the ladder consists of two supporting-sections A and B, a platform C, connected with said members constituting the upper portion of the step-ladder, and hinges D, whereby the sections or members of the ladder are connected. Each side 55 10 of each section or member A and B of the ladder constitutes a portion of a truss, the said sides 10 being cut centrally and longitudinally from their hinged or abutting ends 60 to a point at or near their opposing or outer ends, and the parts formed thereby constitute an upper or outer rail 10^a and an inner or lower rail 10^b, the outer or upper rails being longer than the inner or lower rails, and 65 when the members A and B of the ladder are brought in longitudinal alinement at the front the outer or upper rails 10^a meet at their inner ends, or practically so, to form a continuous or long upright ladder when such form of 70 ladder is required. The rails of the sides of the said supporting-sections A and B are braced between their ends by pins 11, which may be of wood or other material, and these pins 11 constitute struts for the truss portions 75 of the ladder.

The sections A and B of the ladder are connected by hinges D. Each hinge comprises two parts 12 and 13, each part being of angular construction. The body member a of 80 each section of the hinge is usually somewhat curved, as shown in Fig. 2, and the upper ends or those ends which are adapted for attachment to the sections A and B of the ladder are at one side of a line drawn longitudinally through the center of the body-sections of the hinges, and the upper ends of said body-sections a of the hinges are made to engage with the inner faces of the upper or outer rails 10^a of the sections A and B of the ladder 85 at the inner ends of said rails, the connection being effected through the medium of bolts or rivets 14 or their equivalents. The body portion of one section of a hinge is carried over upon the corresponding portion of the 90 other section, and the body portions of the two sections of a hinge are pivotally connected by pins 15 or like devices, as is illustrated in Fig. 2. The foot portion b of each 95 section of a hinge is adapted to engage with a 100

lower or inner rail 10^b, as shown in Figs. 2, 3, and 4. These foot portions of the sections of the hinges are provided with tongues 16, adapted to fit into or enter recesses made in the said rails 10^b. These tongues serve to strengthen the rails 10^b, and the foot portions of the said hinge-sections may be secured rigidly to the said rails 10^b by rivets or their equivalents.

10 It may be here observed that the inner rails 10^b of the section B of the ladder are drawn together at their inner ends to such an extent that they will be within the longitudinal plane of the corresponding rails of the section A, as 15 shown in Fig. 3. Consequently the foot portion of a section of each hinge is attached to the outer face of the contracted rails 10^b, while the foot portions of the other sections of the hinges are secured to the inner faces of the 20 rails 10^b of the opposing section of the ladder. Under this construction it is obvious that the contracted rails 10^b may be carried within the wider-spaced rails of the opposing section of the ladder when the two sections A and B are 25 brought longitudinally together, as illustrated in Fig. 4.

The section A of the ladder, which is the front section when the ladder is used as a step-ladder, is provided with the usual steps 30 17, while the opposing or rear section B of the ladder is provided with corresponding rungs 18, as illustrated in Fig. 1. The platform C for the ladder when used as a step-ladder is provided with transverse flanges 19 near its 35 ends. These flanges are secured to the under face of the platform C and are preferably inwardly curved, as shown in Fig. 3, in order to permit free play of the hinges D. One end of each flange 19 attached to the platform C 40 is pivotally connected at 20 in any suitable or approved manner with the upper inner portion of the section B of the ladder, the attachment being preferably made to the upper or outer rails 10^a, while the opposite end 45 of each platform-flange 19 is connected with the corresponding rail of the section A of the ladder by means of links 21, as best shown in Figs. 2, 3, and 4. Thus in operation when the ladder is set up as a step-ladder the platform C is horizontal, and said platform will 50 not be in engagement with the upper ends of the sections A and B of the ladder, as shown in Fig. 1, and the sections A and B of the ladder may be carried as far apart or as close 55 together as occasion may demand.

When a long ladder is required, the two sections A and B are brought end to end or in longitudinal alinement, the inner ends of the rails 10^a at that time being brought together, as illustrated in Figs. 2 and 3. When the sections of the ladder are in this position, it is evident that each side of the ladder forms a complete truss and that the body portions of the hinges D constitute central 60 struts for each side truss. The sections A and B of the ladder are securely locked in the extended position by causing the plat-

form to drop down upon the upper edges of the two sections, the flanges of the platform being then between the outer or upper rails 10^a, and when the platform is in this position, which is shown particularly in Fig. 2, the links 21 where they connect with the flanges on the platform will be below the center of their pivotal connections with the section 75 A of the ladder. Under such construction it is obvious a lengthy upright ladder may be quickly provided and that the ladder under this arrangement of its parts will be exceptionally light and very strong, and may be 80 therefore readily manipulated and conveniently carried from place to place. The sections of the ladder may be folded so as to produce an ordinary step-ladder by simply carrying the platform C out slightly from the 85 outer faces of the sections A and B and then breaking the sections at their hinged connection. When the members A and B of the ladder are folded longitudinally in engagement with each other, as shown in Fig. 4, the 90 platform is supported by the body portions of the hinges D.

It will be noted that the two sections A and B of the ladder are practically of the same length. Thus when the sections are brought 95 end to end a very long light ladder is obtained. It will also be noticed that when the sections of the ladder are brought end to end the pivots of the hinges are a considerable distance below the platform, which at this time serves 100 as a lock, and, as stated, when the sections of the ladder are folded longitudinally together the hinges extend considerably above the upper edges of said sections.

Having thus described my invention, I 105 claim as new and desire to secure by Letters Patent—

1. A ladder comprising hinged sections, a platform having pivotal connection with one of the sections, and a link connection between 110 said platform and the other section whereby the platform serves as a locking device when the sections are alined, substantially as specified.

2. A folding ladder having truss sides, and 115 hinges for the sections of the ladder, which hinges in one position of the sections constitute struts for the truss sides.

3. A folding ladder having truss sides and hinges for the sections, constituting central 120 struts for the ladder.

4. A folding ladder, a hinged connection between the sections of the ladder, and a platform having pivotal engagement with the sections of the ladder, the platform being 125 supported on said hinges when the sections of the ladder are brought in longitudinal contact.

5. In a folding ladder, the combination, with the sections of the ladder, of hinges constructed in angular pivotally-connected members, the said members being attached to the abutting ends of the said sections of the ladder, and a platform above said abutting ends, 130

having direct pivotal engagement with one of the sections and a link connection with the opposing section of the ladder, as set forth.

6. In a folding ladder, the combination, 5 with the sections of the ladder, of hinges constructed in angular pivotally-connected members, the said members being attached to the abutting ends of the said sections of a ladder, and a platform above the abutting ends of 10 the sections of the ladder and above the said hinges, the said platform being provided with flanges arranged to enter the spaces between the sides of the sections of the ladder, each flange having a direct pivotal connection with 15 one section of the ladder and a link connection with the opposing ladder-section, as described.

7. In a folding ladder, hinges consisting of angular members pivotally connected and arranged to move one upon the other, one section of each hinge member being attached transversely to a side of a section of the ladder at the abutting ends of said sections, the other section of each hinge member extending longitudinally along a side of a ladder-section, and provided with strengthening projections for the ladder-sections, as described. 20 25

In testimony whereof I have signed my name to this specification in the presence of two subscribing witnesses.

WALTER L. SKELLEY.
